UNITED STATES PATENT OFFICE.

FREDERIC WHITAKER, OF PROVIDENCE, RHODE ISLAND.

DESIGN FOR A PENDANT.

Application filed March 22, 1927. Serial No. 21,249. Term of patent 3½ years.

To all whom it may concern:

Be it known that FREDERIC WHITAKER, a citizen of the United States, residing at Providence, of the county of Providence and State of Rhode Island, has invented a certain new, original, and ornamental Design for a Pendant, of which the following is a specification.

I claim:

The ornamental design for a pendant substantially as shown.

In testimony whereof I affix my signature.

FREDERIC WHITAKER.
